INVENTOR

BY *Victor J. Evans*

ATTORNEY

UNITED STATES PATENT OFFICE.

CRANDALL R. HANEY, OF MANSON, IOWA.

CIGARETTE-HOLDER.

1,386,494.

Specification of Letters Patent. Patented Aug. 2, 1921.

Application filed March 13, 1920. Serial No. 365,555.

To all whom it may concern:

Be it known that I, CRANDALL R. HANEY, a citizen of the United States, residing at Manson, in the county of Calhoun and State 5 of Iowa, have invented new and useful Improvements in Cigarette-Holders, of which the following is a specification.

This invention relates to a cigarette holder and has for its primary object the construction of a holder that will enable the user to 10 more artistically hold a cigarette and besides prevent the fingers of the user from coming in contact with the cigarette.

An object of the invention is to provide an 15 artistically constructed holder that may quickly clamp a cigarette.

With these and other objects in view the invention will be better understood from the following detailed description taken in connection with the accompanying drawing wherein—

Figure 1 is a side elevation of the holder.

Fig. 2 is a front elevation.

Fig. 3 is an enlarged view of the clamping 25 ring.

Fig. 4 is a detailed view of the pivot joint.

Again referring to the drawing illustrating one construction of my invention the numeral 1 designates a clamping ring consisting of a stationary portion 2 and a movable portion 3 which is pivoted to the stationary support as indicated at 4. The movable portion 3 is provided with an extension 5 which co-operates with an arcuate leaf spring 6 and is secured to the stationary portion as indicated at 7. A finger piece 8 is formed on the movable portion 3 so that

the latter may be thrown in either of its two positions. Attention is called to the fact that extension 5 is so arranged and co-operates with the spring in such a manner that the yieldable action of the latter will hold the movable portion in either of its two positions, thereby allowing the cigarette to be effectively held in place. The movable 45 portion 2 is connected to a finger ring 9 by the rod 10.

It is of course to be understood that the shape of the various parts may be changed, or artistically engraved and made of any 50 suitable material and, therefore, I do not desire to be limited in any manner except as set forth in the claims hereunto appended.

Having thus described my invention what I claim is—

1. A cigarette holder comprising a clamping ring consisting of two portions pivoted together, a rod connected thereto, and a finger ring connected to the rod.

2. A cigarette holder comprising a ring 60 consisting of a stationary portion and a movable portion pivoted together, a spring for holding the movable portion in either of its two positions, a finger piece connected to the movable portion, a rod connected to the 65 stationary portion, and a finger ring connected to the rod.

3. A cigarette holder comprising a clamping ring consisting of two parts swingingly connected, and a finger rod extending from 70 one of said parts.

In testimony whereof I affix my signature.

CRANDALL R. HANEY.
